Specification for Design.

Patented June 19, 1917.

Application filed April 24, 1917. Serial No. 164,293. Term of patent 3½ years.

To all whom it may concern:

Be it known that I, LUIGI ANGIULLI, a subject of the King of Italy, residing at the borough of Manhattan, city, county, and State of New York, have invented a new, original, and ornamental Design for a Lamp-Stand, of which the following is a specification, reference being had to the accompanying drawings, forming part thereof.

In the drawings, Figure 1 is a side elevation and Fig. 2 is a plan view, of a lamp-stand, showing my new design.

I claim:

The ornamental design for a lamp-stand, as shown.

Signed at the borough of Manhattan, city, county and State of New York, this twentieth day of April, A. D. 1917, in the presence of the two undersigned witnesses.

LUIGI ANGIULLI,

Witnesses:

JAMES HAMILTON,
M. E. WOARDELL.
